(57) **CLAIM**

The ornamental design for a data repeater for wireless communication apparatus, as shown and described.

DESCRIPTION

FIG. 1 is a perspective view of a data repeater for wireless communication apparatus showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a left side view thereof, in an installed position; and,

FIG. 9 is another left side view in an installed position.

The broken line showing of the installation surfaces in FIGS. 8 and 9 is included for the purpose of illustrating environment and forms no part of the claimed design.
